FOOTED TUMBLER OR SIMILAR ARTICLE

Robert Alexander Wilkin, London, England, assignor to
Peter Pan Productions Limited, London, England, a
British company

Filed July 29, 1964, Ser. No. 81,056

Claims priority, application Great Britain Feb. 19, 1964

Term of patent 14 years

(Cl. D36—8)

Fig.1.

Fig.2.

The tumbler or similar article is preferably opaque and circular when viewed in plan.

I claim:

The ornamental design for a footed tumbler or similar article, substantially as shown and described.
